United States Patent Office

Des. 221,820
Patented Sept. 7, 1971

221,820

SMOKING STAND

Miguel Rodrigo Mazure, San Isidro,
Lima, Peru

Filed Feb. 26, 1970, Ser. No. 21,636

Term of patent 14 years

Int. Cl. D27—03

U.S. Cl. D85—2

FIG. 1

FIG. 2

FIG. 3

FIG. 1 is a top plan view of a smoking stand showing my new design;

FIG. 2 is a side elevational view; and

FIG. 3 is a perspective view thereof.

I claim:

The ornamental design for a smoking stand, substantially as shown.
